(57) CLAIM

The ornamental design for a nose insert tip cover, as shown and described.

DESCRIPTION

FIG. 1 is a perspective view of a nose insert tip cover, showing my new design;

FIG. 2 is a left elevation view thereof, the right elevation side view being a mirror image thereof;

FIG. 3 is a front elevation view thereof;

FIG. 4 is a top plan view thereof, the bottom plan view being a mirror image thereof;

FIG. 5 is a rear elevation view thereof; and,

FIG. 6 is a perspective view of the nose insert tip cover, shown in use.

The equal length broken lines showing a nose insert product in FIG. 6 depicts environmental subject matter that forms no part of the claimed design, while the unequal length broken lines shown in the drawings depict the bounds of the claimed article.
